CLAIM

The ornamental design for an olfactory mat for domestic animals, as shown and described.

DESCRIPTION

FIG. 1 is a perspective view of an olfactory mat for domestic animals according to a first embodiment of the new design; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a perspective view of an olfactory mat for domestic animals according to a second embodiment of the new design; FIG. 9 is a front elevation view thereof; FIG. 10 is a rear elevation view thereof; FIG. 11 is a right side elevation view thereof; FIG. 12 is a left side elevation view thereof; FIG. 13 is a top plan view thereof; and, FIG. 14 is a bottom plan view thereof.

The broken lines formed by linear segments of equal length illustrate portions of the article that form no part of the claimed design. The broken lines formed by a dash-dot-dash sequence represent an unclaimed boundary.

1 Claim, 10 Drawing Sheets

Related U.S. Application Data

continuation of application No. 29/579,609, filed on Sep. 30, 2016, now abandoned.
